MODULATED-LIGHT SPEECH TRANSMITTER AND RECEIVER

Gunther K. E. Kleberg, Woburn, Mass., assignor to
Infrared Industries, Inc., Waltham, Mass., a corpora-
tion of Delaware

Filed Sept. 16, 1960, Ser. No. 62,171

Term of patent 14 years

(Cl. D26—14)

FIGURE 1

FIGURE 2

FIGURE 3

FIGURE 1 is a front elevational view of a modulated-light speech transmitter and receiver, showing my new design;

FIGURE 2 is a rear elevational view, and

FIGURE 3 is a side elevational view, the opposite side being substantially a mirror image thereof.

A portion of FIG. 1 is diagonally lined to indicate transparency.

I claim:

The ornamental design for a modulated-light speech transmitter and receiver, as shown and described.
